UNITED STATES PATENT OFFICE

FRANK C. HARRIS, OF CLEVELAND, OHIO

CLOSURE-OPERATED TRACK OPENER

Application filed October 31, 1927. Serial No. 230,139.

My invention is an improvement in closure operated track openers.

One of the objects of my invention consists in the provision of means operable by a closure for automatically opening a track section when the closure is moved across the path of the track in one direction, and to automatically restore the movable track section to its normal closed position when the closure is opened.

Other objects and advantages of my invention will become more apparent as the following description of several embodiments thereof progresses, reference being made to the accompanying drawings in which like reference characters are employed to designate like parts throughout the same.

Fig. 1 is a top plan view of a device embodying one form of my invention;

20 Fig. 2 is a side elevation of the same;

Fig. 3 is a top plan view of a device embodying another form of my invention, and

Fig. 4 is a side elevation of the device shown in Fig. 3.

25 In the drawings in Figs. 1 and 2, I have illustrated one embodiment of my invention which is adapted particularly for use in connection with vertically moving closures, while in Figs. 3 and 4, I have illustrated another form of my invention adapted particularly for use in connection with horizontally moving closures.

In Figs. 1 and 2, a rail section 3 is suspended by means of a bracket 2 from the under side of the wall 4' defining an opening through the wall through which sections of an overhead track, such as a monorail system, may pass. The rail section 4 is in alignment with the rail section 3 and is likewise suspended from the wall 4' by a similar bracket (not shown) arranged on the opposite side of the opening in the wall 4'. Pivotally secured to the rail section 4 is a rail section 5 pivoted at 6. When the closure 7 is in open position the rail section 5 is swung to the position shown in Fig. 2 and bridges the gap between the sections 3 and 4 forming a continuous suspended rail along which suitable carriers may pass.

45 50 It will be noted that the rail section 3

does not extend through the opening closed by the closure 7, thus permitting a closure such as a firedoor or the like to move to close the opening in the wall when the track section 5 is swung out of the path of the closure. 55

A plate or the like 8 is secured to the movable rail section 5 in any suitable manner and is movable with it about the pivot 6. A portion 9 of the plate 8 extends forwardly bringing the adjacent ends of the rails 3 and 5 into alignment and acts as a stop when the movable rail 5 is swung into alignment with the sections 3 and 4, the under surface of the stop 9 resting on the upper surface of the rail section 3. The adjacent edges of the rails 3 and 5 may be disposed slightly out of the vertical plane as shown at 9' to further stop the downward swing of the section 5 beyond a certain degree and to allow clearance for the rail 5. A connecting rod 10 is pivotally secured at one end to the member 8 by means of a pin 11. Its other end extends through an opening formed in the bracket arm 12 and is screw-threaded and passes through an opening in a bracket-arm 12. Nuts 13 are provided for adjustment. A coil spring 14 is carried by the rod 10 abutting at one end against the support 24 and at its other end against a stop on the rod 10 and provides a yielding connection between the trip and the movable rail section exerting its force to normally return the rail section 5 to the position shown in Fig. 2 when the closure is opened. The bracket-arm 12 is preferably formed of angle iron having a depending flange 15 which is provided with the opening through which the connecting rod 10 passes. The opposite end of the arm 12 is pivotally connected to a movable trip 16 by means of a pin 17. The trip comprises a main body portion 16 having a closure engaging portion 18 formed at one end to extend into the path of movement of the closure 7. The trip 16 is provided with a rearwardly extending arm 19 which is pivotally connected to a bracket-bar 20 by means of a pin 21. The bracket-bar 20 is supported by means of suitable bolts 22, to extend forwardly of the plate 23. The plate 23 is preferably formed of suitable angle iron, the base of which is secured to a support 24 by 100

means of the bolts 25. The support 24 is secured to the fixed rail section 4 in any suitable manner.

In Figs. 3 and 4, I have provided means 5 for opening a section of continuous track to permit a closure of the horizontally moving type to pass freely through the opening formed in the track. This embodiment of my invention is similar in many respects to the 10 embodiment illustrated in Figs. 1 and 2, although it differs materially in some respects. One section 30 of a system of suspended trackage is fixed to a depending bracket 29 by suitable means, the bracket 29 being supported 15 from a suitable ceiling support. In this form of my invention I have illustrated in Figs. 3 and 4 the invention as applied to a system of overhead trackage such as overhead monorail systems in which a horizontally 20 moving closure actuates means for automatically removing a section of track section to its original position when the closure is moved to open position.

It is to be understood that the embodiments 25 of my invention illustrated in Figs. 1 to 4, inclusive, may be used in connection with any system of trackage including overhead and monorail systems. In Figs. 3 and 4 a horizontally moving closure is illustrated at 30 31 and is movable through the opening formed between the fixed track sections 30 and 32 when the movable track section 33 is swung about its pivot 34.

In this embodiment of my invention, I 35 have provided suitable means whereby the track section 33 may be swung about its pivot 34 to open position, said means including a trip located in the path of movement of the closure, thus permitting the closure to pass 40 through the opening formed in the track section. The trip 35 is pivotally mounted by means of a pin 36 to a bracket plate 37. The plate 37 is secured to a suitable support 38 by means of bolts or the like 39. One end of 45 the trip 35 is pivotally connected to a bracket-arm 40 by means of a pin 41. The arm 40 extends rearwardly and terminates in a curved portion 42. The curved portion is provided with an opening through which the threaded end of a connecting rod 43 extends. This end of the connecting rod carries adjusting nuts 44. A coil spring 50 is telescopically arranged on the rod 43 and provides a flexible connection between the trip and the 50 movable rail 33. The other end of the connecting rod 43 is pivotally connected by means of a pin 45 to a plate 46. The support 38 is secured to the fixed rail section 32 while the bracket member 46 is secured to 55 move with the movable rail section 33. The forward end of the plate 46 bridges the joint between the movable rail section 33 and the fixed section 30 when the two sections are 60 in alignment, and acts as a stop for the movable rail section 33. This is shown at 47.

The operation of the device illustrated in Figs. 1 and 2 is as follows:

With the parts in the position shown in Figs. 1 and 2, the track sections are all in alignment providing a continuous track 70 through a wall opening, such as a firedoor frame or the like, which track is adapted to carry the wheels of a carrier upon the lower flanges thereof. When it is desired to move the closure which in the present instance is 75 a vertically moving closure 7, to closed position, it is moved in the direction of the arrow, until it engages the end 18 of the trip 16. Continued movement of the closure 7 in the direction of the arrow will swing the trip 16 80 about its pivot 21 and will move the arm 12 to the left as in Fig. 2. As the arm moves to the left the depending flange 15 engages the adjusted nuts 13 moving the connecting rod 10 to the left against the compression of the 85 spring 14, and swinging the plate 8 and the movable rail section 5 about the pivot 6, opening a section of the track in the path of movement of the closure, and permitting the closure to pass through the opening to close the 90 opening in the wall. When it is desired to open the closure 7, that is, by moving it in a direction reverse to that of the arrow shown in Fig. 2, and closing the track section 5, this is accomplished by moving the closure upwardly through the opening formed between the fixed track sections 3 and 4 whereupon the spring 14 on the connecting rod 10 will exert its compression against the rear end of 95 bracket 24 and the plate 8 to swing the plate 100 and the movable track section 5 downwardly to the position shown in Fig. 2, closing the opening in the track section and again restoring the track-sections 3, 4 and 5 in aligned position.

The operation of the apparatus illustrated in Figs. 3 and 4 is similar to that just described in connection with Figs. 1 and 2 except that the closure is of the horizontally moving type, and the trip is movable about a 110 vertical axis instead of a horizontal axis as shown in Figs. 3 and 4.

It is obvious that various changes may be made in the details of construction of my invention without departing from the spirit 115 thereof or the scope of the appended claims.

I claim:

1. A monorail track system including a pair of spaced track sections, a movable section connected to one of said sections and normally bridging the space therebetween, closure means for moving the movable section to permit a closure to pass between the spaced track sections, and means releasable to return the movable section to its initial position 120 when the closure is withdrawn from between the spaced track sections.

2. A monorail track system including a pair of spaced track sections, a movable section connected to one of said sections and nor- 130

normally bridging the space therebetween, and closure operated means for moving the movable section, and means releasable to return the movable track to its initial position when
 5 the closure is withdrawn from between the spaced track sections, said last named means comprising a coiled spring compressible by the movable section in its movement out of its normal position.

10 3. A monorail track system including a pair of fixed spaced track sections, a track section pivoted to one of said fixed sections and normally bridging the space therebetween, and closure operated means for swing-
 15 ing the movable section to permit a closure to pass between the spaced sections, said means including a closure operated trip and means connecting the trip with the movable track section for moving the same when the trip
 20 is actuated.

4. A monorail track system including a pair of fixed, spaced track sections, a movable section pivoted to one of the fixed sections and normally bridging the space there-
 25 between, a support for one of the fixed sections a trip pivoted to said support and in the path of movement of a closure, means connecting the trip with the movable track section, and compression means releasable
 30 when the closure is removed from between the spaced sections, to return the movable section to its normal position.

5. A monorail track system including a pair of fixed, spaced track sections, a movable section pivoted to one of the fixed sections and normally bridging the space between said fixed sections, a support for one of the fixed sections, a trip pivoted to said support and in the path of movement of a closure, a rod
 40 connected to the movable section, a link connect-
 ing the rod with the trip, and means carried by the rod to return the movable section to its normal position bridging the spaced fixed sections when the closure is withdrawn
 45 from the space between the fixed sections.

6. A monorail track system including a pair of fixed, spaced track sections, a movable section pivoted to one of the fixed sections and normally bridging the space therebe-
 50 tween, a support for one of the fixed sections, a trip pivoted to said support and in the path of movement of a closure, a rod connected to the movable section, a link connect-
 ing the rod with the trip, and a coiled spring
 55 telescoping the rod and abutting the said support, said spring being compressible by the movement of the movable section out of its normal position, to return the movable section to its normal position when the clo-
 60 sure is removed from the space between the fixed sections.

In testimony whereof I hereunto affix my signature this 17th day of October, 1927.
